Attorney

UNITED STATES PATENT OFFICE.

LEAMAN A. CORKUM, OF SOMERVILLE, MASSACHUSETTS.

EXTRACTOR.

Application filed September 2, 1927. Serial No. 217,077.

My present invention relates to extractors, and more particularly to tools or devices for use in extracting such articles as gear keys, pulley keys, or the like.

5 Great difficulty has been heretofore experienced in extracting such devices as keys from gears, pulleys, or the like, especially in the larger sized keys, which are usually driven in under considerable pressure. 10 When it has become necessary to remove these keys, for repair work or any other purpose, it has frequently been found extremely difficult to dislodge the same. In actual practice, many methods are utilized, such as 15 attempting to drive the keys out with sledges and cold chisels. This frequently results in the destruction of the keys, which, in these larger sizes, are expensive. Also, a great length of time is required to remove keys by 20 such methods, resulting in unnecessary delay, expense and annoyance.

My present invention provides a device which will readily remove the most refractory key, and which will remove it in such a 25 way as to preserve the key, enabling it to be used over and over again, my novel device not materially marring or injuring the keys during removal.

The present invention comprises a pair of 30 pivoted arms, carrying at one end a pair of jaws adapted to engage and grip the projecting end of a gear key, pulley key, wheel key or the like. These jaws are so mounted on the arms as to provide the point of greatest 35 pressure on the key nearest the outer end of the jaws, thus insuring constantly increasing pressure of the jaws on the key when removing same.

These and further features of the invention 40 will be hereinafter more fully described.

Further features of the invention, details of construction, combinations and advantages, will be hereinafter more fully pointed out and claimed.

45 Referring to the drawings, illustrating a preferred embodiment of the invention,

Fig. 1 is a plan view, partly broken away, of the device; and

50 Fig. 2 is a longitudinal sectional view on the line 2—2 of Fig. 1.

As shown in the drawings, my present novel device comprises a substantially U-shaped frame comprising an end portion 1, and sides 2 and 3. This frame is preferably 55 formed of channel members and may be made as an integral unit. The outer ends

of the arms 2 and 3 are adapted to abut against the hub 4 of a pulley, gear, wheel or the like 5. A key 6 is illustrated, fitting in the keyway 7 in the shaft 8 on which the gear 5 is mounted. These keys, particularly in the larger sizes, are quite expensive, and heretofore, in removing them, they have frequently been irreparably damaged and incapable of further use. Also, it has been 60 found that a great length of time is required to remove these keys, particularly as they must be wedged or jammed in in order to effect a tight holding of the gear or the like on the shaft. Cold chisels, hammers and 65 the like have been necessary to effect the removal of these keys, necessarily resulting in great damage thereto.

In my present device I provide a pair of jaws 9, 9, secured to the ends of arms 10, 10, 70 by set screws 11, 11, or other holding devices. The jaws 9 are yoked at their inner sides to fit over the ends of the arms 10, as clearly illustrated, and the outer ends of the arms 10 are so formed with respect to the 75 yoked portions of the jaws 9 that the portions 12, 12, of the arms engage the outer ends of the jaws, the arms 10 being jogged at 13 to engage shoulders 14 on the jaws 9. In this manner, when pressure is exerted 80 against the jaws, the point of greatest pressure will be at the point 12, where the arms 10 bear against the jaws 9.

The arms 10 are pivoted to the yoked ends of a crossbar 15 at 16, 16, the sides of the arms, and the pivot points, being carried within the channels of the sides 2 and 3. A threaded stem 17 is fitted through the end 1 of the frame, this stem having a squared end 18 and a nut 19 is provided on the stem 90 outside of the frame, a bearing washer 20 being interposed between the nut 19 and end 1 of the frame. This threaded stem 17 extends into the frame and through the crossbar 15 and has a nut 21 on its inner end, a 100 recess 22 being provided in the crossbar 15 to provide for longitudinal adjustment of the stem 17 by accommodating the nut 21. The threaded portion of the stem terminates 105 before reaching the crossbar 15, and interposed between the end of the thread and the crossbar 15 is a bearing washer 23. A yoked cross-arm 24 is threaded on the stem 17, and the yoked ends of the arm 24 straddle the arms 10. The faces 25 of the arm 24, which 110 engage the inner sides of the arms 10, are inclined toward the rear of the arms.

The operation of my present novel device is simple, and will be readily understood, being described as follows:

The device being applied to an article from which it is desired to remove a key, or the like, such as the key 6, and the ends of the sides 2 and 3 of the frame engaging the hub 4, the stem 17 is rotated by turning of the squared end 18. This causes the washer 23 to be forced against the crossbar 15, and by reason of the threads in the cross-arm 24, will cause the cross-arm 24 to move toward the ends 26 of the arms 10, the inclined faces 25 bearing against the inner sides of the arms 10 and forcing them apart, the pressure thus exerted bringing the jaws 9 toward each other and sinking the teeth 27 into the key or other device to be extracted.

The fact that the ends of the arms 10 bear primarily and with greatest force, against the outer ends of the jaws, gives the point of greatest pressure at this particular location. When the teeth have been sunk into the key a sufficient distance, rotation of the stem 17 by means of the squared end 18 ceases, and rotation is then imparted to the nut 19, by wrench or other instrumentality. This rotation of the nut 19 will cause the stem 18 to be threaded outwardly through the nut 19, without rotation of the stem 17, and consequently will draw the crossarm 24, and hence the arms 10, cross-bar 15 and jaws 9, toward the end 1 of the frame, resulting in positively extracting the key 6 from its key-way 7. This extracting operation will not cause material damage to the key, but permits the key to be used over and over again.

Upon completion of the extracting operation, rotation of the squared end 18 of the stem 17 in the opposite direction will cause the cross-arm 24 to ride on the stem 17 toward the crossbar 15, permitting the release of the jaws 9 from the key 6 and leaving the device in position for repetition of the extracting operation.

It will thus be seen that I have devised a novel extracting device, one which is simple in construction and operation, and yet which is efficient and positive in its extracting, insuring removal of the keys in a short space of time and with a minimum of injury or damage thereto.

The space 28, left between the arms 10 and jaws 9, permits a slight "give" of the jaws when the pressure thereon is increased. It will also be noted that the teeth 27 are shaped so as to be pointed in the direction of pull, as well as being backed up by a considerable portion of metal, 29, with no teeth thereon, thus insuring against breakage of the teeth because of insufficient metallic backing or strength.

I believe that my present key extractor,

as above described, is novel, and I have therefore claimed the same broadly herein.

While I have necessarily described my present invention somewhat in detail, it will be appreciated that I may vary the size, shape and arrangement of parts within reasonably wide limits without departing from the spirit of the invention.

A further advantage in the construction illustrated and described herein is the fact that the jaws 9 are removable and replaceable. Thus, if any of the teeth should chip or wear off, either or both of the jaws can be readily removed and replaced, thus still further increasing the desirability, efficiency, and economy of the present device.

My invention is further described and defined in the form of claims as follows:

1. An extractor of the kind described, comprising a substantially U-shaped frame, a threaded stem carried in said frame, means to rotate said stem, a cross-bar carried by said stem, a pair of arms pivoted to said crossbar, jaws on one end of said arms, and a cross-arm threaded on said stem and engaging said arms, said cross-arm being adapted, on rotation of the stem, to move said jaws to clamping position.

2. An extractor of the kind described, comprising a substantially U-shaped frame, a threaded stem carried in said frame, means to rotate said stem, a cross-bar carried by said stem, a pair of arms pivoted to said crossbar, jaws on one end of said arms, a cross-arm threaded on said stem and engaging said arms, said cross-arm being adapted, on rotation of the stem, to move said jaws to clamping position, and means to move said jaws toward and from an article to be extracted.

3. An extractor of the kind described, comprising a substantially U-shaped frame, a threaded stem carried in said frame, means to rotate said stem, a cross-bar carried by said stem, a pair of arms pivoted to said crossbar, jaws on one end of said arms, and a cross-arm threaded on said stem and engaging said arms, said cross-arm having inclined faces engaging the inner sides of said arms and adapted, on rotation of the stem, to move toward the outer ends of said arms, separating said outer ends and bringing said jaws into clamping position.

4. An extractor of the kind described, comprising a substantially U-shaped frame, a threaded stem carried in said frame, means to rotate said stem, a cross-bar carried by said stem, a pair of arms pivoted to said cross-bar, jaws on one end of said arms, a cross-arm threaded on said stem and engaging said arms, said cross-arm having inclined faces engaging the inner sides of said arms and adapted, on rotation of the stem, to move toward the outer ends of said arms, separating said outer ends and bringing said

jaws into clamping position, the thread on said stem terminating before reaching said cross-bar, and a bearing member interposed between the end of the thread and said cross-bar.

5. An extractor of the kind described, comprising a substantially U-shaped frame, a threaded stem carried in said frame, means to rotate said stem, a cross-bar carried by 10 said stem, a pair of arms pivoted to said crossbar, jaws on one end of said arm, a cross-arm threaded on said stem and engaging said arms, said cross-arm having inclined faces engaging the inner sides of 15 said arms and adapted, on rotation of the stem, to move toward the outer ends of said arms, separating said outer ends and bringing said jaws into clamping position, the thread on said stem terminating before 20 reaching said crossbar, a bearing member interposed between the end of the thread and said crossbar, and a nut on the inner end of said stem.

6. An extractor of the kind described, 25 comprising a substantially U-shaped frame, a threaded stem carried in said frame, means to rotate said stem, a cross-bar carried by said stem, a pair of arms pivoted to said crossbar, jaws on one end of said arms, a cross-arm threaded on said stem and engaging said arms, said cross-arm having inclined faces engaging the inner sides of said arms and adapted, on rotation 30 of the stem, to move toward the outer ends of said arms, separating said outer ends and bringing said jaws into clamping position, the thread on said stem terminating before reaching said crossbar, a bearing member interposed between the end of the thread 35 and said crossbar, and a nut on the inner end of said stem, said crossbar having a recess to receive said nut and permit longitudinal adjustment of said stem.

7. An extractor of the kind described, 40 comprising a substantially U-shaped frame, a threaded stem carried in said frame, means to rotate said stem, a cross-bar carried by said stem, a pair of arms pivoted to said crossbar, a removable jaw pivotally mounted 45

on one end of each arm, and means to move 50 said jaws to clamping position.

8. An extractor of the kind described, comprising a substantially U-shaped frame, a threaded stem carried in said frame, means to rotate said stem, a cross-bar carried 55 by said stem, a pair of arms pivoted to said cross-bar, a removable jaw pivotally mounted on one end of each arm, and a cross-arm threaded on said stem and engaging said arms, said cross-arm being adapted, on 60 rotation of the stem, to move said jaws to clamping position.

9. An extractor of the kind described, comprising a substantially U-shaped frame, a threaded stem carried in said frame, means to rotate said stem, a cross-bar carried by 65 said stem, a pair of arms pivoted to said cross-bar, a removable jaw pivotally mounted on one end of each arm, a cross-arm threaded on stem and engaging said arms, 70 said cross-arm being adapted, on rotation of the stem, to move said jaws to clamping position, and means to move said jaws toward and from an article to be extracted.

10. An extractor of the kind described, 75 comprising a substantially U-shaped frame, a threaded stem carried in said frame, means to rotate said stem, a cross-bar carried by said stem, a pair of arms pivoted to said cross-bar, a removable jaw pivotally mounted 80 on one end of each arm, a cross-arm threaded on said stem and engaging said arms, said cross-arm having inclined faces engaging the inner sides of said arms and adapted, on rotation of the stem, to move 85 toward the outer ends of said arms, separating said outer ends and bringing said jaws into clamping position, the thread on said stem terminating before reaching said crossbar, a bearing member interposed between 90 the end of the thread and said cross-bar, and a nut on the inner end of said stem, said cross-bar having a recess to receive said nut and permit longitudinal adjustment of said stem.

In testimony whereof, I have signed my 95 name to this specification.

LEAMAN A. CORKUM.
